CONTAINER FOR PAPER NAPKINS OR THE LIKE

Nathan Shapira, Los Angeles, Calif., assignor to Cartiera di Cairete S.p.A., Milan, Italy

Filed July 17, 1967, Ser. No. 7,816

Claims priority, application Italy May 8, 1967

Term of patent 14 years

(Cl. D52—2)

What I claim is:

The ornamental design for a container for paper napkins or the like, substantially as shown.
